QUENCHING AND CUTTING OIL COMPOSITION

Karl-Heinz Kopietz, Hildesheim, Germany, assignor to
 Houghton-Chemie G.m.b.H., Hildesheim, Germany
 No Drawing. Filed Apr. 11, 1958. Ser. No. 727,774
 Claims priority, application Germany Apr. 13, 1957
 2 Claims. (Cl. 148—18)

The invention relates to quenching and cutting oils and more particularly to such oil compositions which are readily removed from the treated metal pieces by washing with water.

Heretofore, the water-insoluble quenching or cutting oils had to be removed from the treated work pieces by means of hot alkaline solutions or organic solvents.

This cleaning process is expensive and time consuming, and it has frequently been omitted even in cases where it is actually required. It would, therefore, be of great advantage if the cleaning procedure could be cheapened and simplified.

It is a principal object of the invention to provide cutting and quenching oil compositions which are readily removable from the work pieces after treatment.

Other objects and advantages will be apparent from a consideration of the specification and claims.

According to the invention, oil compositions are used for quenching and cutting purposes which contain a heat stable non-ionic, non-saponifiable (saponification No. ≤ 2) polyethenoxy surfactant. Such surfactants are well known and available in commerce under various trademarks, for instance under the names Stokolan (Chemische Fabrik Stockhausen & Cie.), Emulphor and comprise for instance polyethenoxy ethers of fatty alcohols, such as those of hexyl alcohol, heptyl alcohol, dodecyl alcohol, tetradecyl alcohol, oleic alcohol, stearic alcohol, and mixtures of such alcohols, and polyethenoxy esters. Particularly useful are polyethenoxy alkyl phenols alone or in combination with other polyethenoxy compounds.

As alkyl phenol component, alkyl phenols having one or more alkyl groups of about 6 to 18 C atoms may be used, for instance diethyl, p-tert. octyl, noyl phenol. I found particularly suitable polyethenoxy emulsifiers which are co-condensation-products of pure aliphatic and phenol-substituted aliphatic glycols. The emulsifiers used must be either completely or partially soluble in the oil or must be able to form stable suspensions. Preferably, they are incorporated in the oil either in the form of a molecular dispersion or in the form of a stable suspension.

The emulsifier should be present in the oil in amounts of about 1 to 15, preferably 2 to 5 percent by weight of the oil.

Stabilizers and inhibitors, for instance anti-oxidants, may be added in amounts of about 0.5 to 3 percent by weight to prevent decomposition of the emulsifiers. A suitable stabilizer is, for instance, oleyl alcohol.

When the recited emulsifiers are used, the oil film remaining on the surface of the work pieces is readily removed by spraying with water or by dipping the work piece in water. The water temperature has no appreciable influence on the cleaning effect, and it is usually sufficient to use cold water. The cleaning effect is so good that practically no oil remains on the work pieces, particularly if the pieces are sprayed with water. In dip-cleaning, the water becomes enriched with oil and is eventually converted to an oil-in-water emulsion. In this case, a thin oil film remains on the work piece after evaporation of the water. In this way, it is possible either to obtain a clean completely oil-free surface on the work piece by spraying with water, or to retain a fine, rust-protecting oil film by the dipping procedure. Said film

2

is formed from the oil-in-water emulsion and can be removed later by spraying.

The protection of the work pieces by a removable oil film makes it possible to store the pieces for any length of time without risk of rust formation and to remove the oil film only shortly before tempering. This presents great advantages over the conventional cleaning procedure with vaporized chlorinated hydrocarbons (trichloroethylene, perchloroethylene) where the metal surface is rendered completely free of oils and fats so as to make rusting unavoidable on storage.

The oils used as quenching and cutting oils are well known to the skilled in the art. Any such oil may be combined with the recited emulsifiers to form the water-removable compositions of the invention. Instead of mineral oils, also other oily liquids may be used, which have quenching properties similar to mineral oils.

I have found that the addition of the recited emulsifier does not substantially affect the quenching effect of the oil. It is, therefore, possible to convert any oil having the desired quenching properties to a water-removable oil composition, which allows of adopting the invention in any plant without changing otherwise the type of oil used.

25 The following examples are given to illustrate the use of said compositions.

EXAMPLE 1

Hardening of Pinion Gear in Flame-Hardening Machines

30 In the flame hardening of the gears of chain drives in a machine for hardening the perimeters of toothed wheels, a compound high duty quenching oil of the following composition is used.

	Percent
35 Refined spindle oil (viscosity 1.6° E./50° C. _____	87
High molecular residue from crude oil refining _____	8
Emulsifier 62082 of Chemische Fabrik Stockhausen & Cie., Krefeld (Germany) _____	4.5
40 Oleic alcohol (iodine number 80-85) _____	.5

45 The product 62082 is a polyalkyleneglycol derivative consisting of a combination of a chain of about 4 ethylene-glycol units with one 2-phenyl-propyleneglycol unit each in terminal position. It has a molecular weight of about 465.

50 After hardening, the toothed wheels are washed in a container of cold water. This procedure is considered particularly pleasant because the operators have always clean hands and the gears are transferred to further processing in clean condition.

EXAMPLE 2

Thermal Refinement of Small Work Pieces

Heretofore, punched and bent spring steel parts of a thickness of about .5 mm. were hardened in quenching oil, which could not be rinsed off with water, and then tempered in a circulating air oven. Prior to tempering, the springs were cleaned with chlorinated hydrocarbons. In this way, the surface was completely freed from oil but the parts became sometimes rusty even before tempering.

60 This drawback was eliminated by using a straight quenching oil of the following composition:

	Percent
65 Refined spindle oil (viscosity 2.2° E./50° _____	95
Oleylpolyethyleneether "Emulphor P" of BASF Bad. Anilin & Sodaefabrik, Ludwigshafen (Rhine) _____	4.5
Oleylalcohol (iodine number 80-85) _____	.5

65 After hardening the parts are washed in a shower of cold water and are placed in the tempering oven. Over weekends, the hardened spring parts, which are wetted with the quenching oil, can be stored, whereby the oil film

acts as anticorrosion agent. On the following Monday, the parts are tempered, whereby the oil film can be previously removed by washing without any difficulty.

EXAMPLE 3

Heat Treatment of Die-Forged Parts

Heretofore, die-forged parts were hardened in a compound high duty quenching oil 1.6° E./50° C. and subsequently without cleaning tempered in an air circulating oven. The heated oil naturally developed large amounts of obnoxious smoke. The inflammable atmosphere formed in the oven was liable to produce dangerous explosions.

According to the invention, the forged parts are hardened in a water-removable high duty compound quenching oil of the following composition:

	Percent
Refined spindle oil, viscosity 2.2° E./50° C.	85
High molecular weight residue from crude oil refining	10
Emulsifier 62082 of Chemische Fabrik Stockhausen & Cie. (Stokolan AW6)	4.5
Oleic alcohol (iodine number 80-85)	.5

Subsequently, the parts were cleaned in water of about 60-80° C. The cleaned parts are tempered without difficulty.

EXAMPLE 4

Induction Hardening of Cam Shafts From Pearlitic Castings for Automobile Engines

Water quenching cannot be applied to such castings because it would produce waste in an amount of about 20 percent, due to heat cracks.

Heretofore, cam shafts were quenched in a conventional quenching oil of 4.5° E./50° C. Subsequently, the parts were cleaned in boiling water containing alkaline cleaning agent to remove the adhered oil.

According to the invention, the conventional lengthy cleaning procedure is eliminated by the use of an emulsifiable quenching oil of the following composition:

	Percent
Refined spindle oil, viscosity 4.5° E./50° C.	93
Emulsifier 62082 of Chemische Fabrik Stockhausen & Cie	6
Oleylalcohol (iodine number 80-85)	1

Rinsing the castings in water of about 40° C. removed the oil within a few seconds.

The invention is useful not only for quenching oils but also for cutting oils, where also oils found suitable may be continued for use with addition of the emulsifier.

EXAMPLE 5

Hob Cutting of Key-Ways in Key Shafts

Key shafts for agricultural machines made from soft annealed steel containing 0.15% C, 1.2% Mn, and 1.1% Cr were heretofore milled with a cutting oil which could not be emulsified in water. Subsequently, the shafts were bored several times, whereby a boring oil emulsion was used. In order to prevent a contamination of the boring oil with the adhered cutting oil, the parts were cleaned between the two operations in a washing machine with a hot alkaline solution.

According to the invention, said wash step can be eliminated by the use of a water-emulsifiable cutting oil of the following composition:

	Percent
Refined mineral oil containing about 3.5% S (0.5% as dissolved free sulfur), viscosity 2.5° E./50° C.	91
Chlorinated paraffin (50% Cl)	4
Emulsifier	4
Oleylalcohol (iodine number 80-85)	1

After milling, the shafts were dipped in water of about

60 to 70° C. to remove the oil. The water is renewed every 8 hours.

After dipping, the work pieces are substantially clean, and no contamination of the boring oil emulsion in the boring step is observed. In this way, the expensive washing operation is no longer necessary.

The used emulsifier is a condensation product of one mol nonyl phenol with six moles ethylene oxide having a molecular weight of 484.

10

EXAMPLE 6

Thread Grinding

In the procedure used before adoption of my novel method, a conventional cutting oil available in commerce was employed for the thread grinding in a machine of the type built by Lindner of Berlin-Whittenan, Germany. The material used was a steel containing 0.58% C, 1.20% Cr, 0.11% V, 0.80% Mn, which had been tempered to a Brinell hardness of 150 kg./mm.².

In said procedure, the adhered grinding oil had to be removed in a cleaning plant operated with vaporized chlorinated hydrocarbons. If the cleaning operation was omitted, the residual grinding oil frequently produced corrosion, even though anticorrosion agents had been applied.

Such corrosion was effectively prevented when the same grinding oil was used under the same conditions with an addition of 5 percent by weight, calculated on the oil, of the emulsifier 62082 of the composition recited in Example 1. Under these conditions, the oil was completely removed by spraying with cold water.

20

EXAMPLE 7

Gear Cutting of Bevel Gears for Automobiles

Bevel gears for automobiles made from a coarse grained annealed steel containing 0.16% C, 1.1% Mn and 1.4% Cr were heretofore cut with a conventional oil, cleaned with trichloroethylene and coated with a rust-preventing emulsion. The subsequent gas carburization was carried out in conveyor ovens with a carrier gas containing small amounts of propane. In this operation, any residual oil on the gears had to be avoided because it would harmfully affect the gas atmosphere. For this reason it was necessary to remove the rust-preventing oil in a washing plant.

By using a cutting oil composition according to the invention, it has become possible to store the cut gears without the risk of corrosion until they were subjected to carburization. Immediately prior to carburization, the gears were sprayed with clear warm water and passed free from any oil films into the carburizing oven. This change of the procedure to an emulsifier containing cutting film resulted in a considerable simplification and economization of the process.

30

The used cutting oil had the following composition:

	Percent
Mineral oil as in Example 5	88
Mixture of metal soaps, vegetable and animal oils	5
Rustproofing agent (Mersol-amino-acetate)	2
Emulsifier as in Example 5	4.5
Oleyl alcohol (iodine number 80-85)	0.5

40

Preferred emulsifiers are condensation products of an alkyl phenol containing an alkyl of 6 to 12 carbon atoms with 3 to 15 moles of ethylene oxide, especially condensation products of one mol of nonyl phenol with six moles of ethylene oxide and of a mean molecular weight of 480 to 490.

I claim:

1. A method of heat treating steel parts comprising hardening said parts in a quenching oil consisting essentially of a mineral oil and about 1 to 15 percent by weight of a condensation product of one mole of an alkyl phenol containing an alkyl of 6 to 12 carbon atoms

50

60

70

75

5

with 3 to 15 moles of ethylene oxide as a nonionic non-saponifiable emulsifier, and spraying off the quenched parts with water thereby completely removing adhered quenching oil.

2. The method as defined in claim 1 wherein said emulsifier is the condensation product of one mol of nonyl phenol with six moles of ethylene oxide having a mean molecular weight of about 480 to 490.
